UNITED STATES PATENT OFFICE.

JOHN N. SCHIPEK AND ANTHONY VEDOVELLI, OF CHICAGO, ILLINOIS.

DESIGN FOR AN OBSERVATORY.

SPECIFICATION forming part of Design No. 20,004, dated July 8, 1890.

Application filed March 22, 1890. Serial No. 344,859. Term of patent 7 years.

To all whom it may concern:

Be it known that we, JOHN N. SCHIPEK and ANTHONY VEDOVELLI, both citizens of the United States, and residents of Chicago, in the county of Cook and State of Illinois, have invented and produced a new and original Design for an Observatory, of which the following is a specification.

Our design relates to the class of observatory represented by the well-known Eiffel Tower; and our object is to provide such an observatory in a novel design which shall not only be attractive and desirable by reason thereof, but shall enable it to be a lasting monument to the subject it is intended to memorialize.

In the accompanying drawing our design is represented in perspective in the form of a horseshoe spanning a street.

The structure in the representation illustrating our design is an observatory in the form of a horseshoe, and it is shown as sup-

ported in vertical position with its ends on bases in the form of step-like approaches to the observatory.

The leading feature of our design comprises an arch form springing from two pedestals and meeting in a central portion, and having at its summit an ornamentation in the form of an observation-platform. In the respective bases of the arch openings are shown occupying the positions of the heel-calks on the conventional horseshoe, while the observation-platform is located in the place of the toe-calk on the conventional horseshoe.
